CLAIM

The ornamental design for a glass breaking cap for flashlights and batons, as shown and described.

DESCRIPTION

FIG. 1 is a perspective view of a glass breaking cap for flashlights and batons showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view thereof having a screw thread;

FIG. 9 is a perspective view thereof attached onto the top of a police flashlight; and,

FIG. 10 is a perspective view thereof attached onto the top of a police baton.

The broken line illustration of a portion of the glass breaking cap in FIG. 7, the screw thread in FIG. 8, the flashlight in FIG. 9 and the baton in FIG. 10 form no part of the claimed design.
